Primary Examiner — Charles D Hanson*(74) Attorney, Agent, or Firm* — Morgan, Lewis & Bockius LLP(57) **CLAIM**

The ornamental design for an electric wheelchair, as shown and described.

DESCRIPTION

FIG. 1 is a front perspective view of an electric wheelchair showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged rear perspective view of the tie-rod and suspension springs of the electric wheelchair shown in FIG. 2; and,

FIG. 10 is an enlarged right-side elevational view of the tie-rod and suspension springs of the electric wheelchair shown in FIG. 6.

The broken lines immediately adjacent the shaded areas represent the bounds of the claimed design while all other broken lines are directed to environment and are for illustrative purposes only; the broken lines form no part of the claimed design.

1 Claim, 10 Drawing Sheets(56)
